UNITED STATES PATENT OFFICE

157,363

LID FOR A BEVERAGE BREWER

Samuel H. Frankel, Chicago, Ill., assignor to Cory Corporation, Chicago, Ill., a corporation of Delaware

Application December 14, 1948, Serial No. 150,136

Term of patent 14 years

(Cl. D44—26)

To all whom it may concern:

Be it known that I, Samuel H. Frankel, a citizen of the United States, residing at Chicago, in the county of Cook and State of Illinois, have invented a new, original, and ornamental Design for a Lid for a Beverage Brewer, of which the following is a specification, reference being had to the accompanying drawing, forming part thereof, wherein—

Figure 1 is a perspective view, looking downwardly, of a lid for a beverage brewer, showing my new design; and

Fig. 2 is a side elevation thereof.

I claim:

The ornamental design for a lid for a beverage brewer, as shown.

SAMUEL H. FRANKEL.
